UNITED STATES PATENT OFFICE.

LEVI C. KENTON, OF BALTIMORE, MARYLAND, ASSIGNOR OF ONE-HALF TO
JAMES CLEMENT, OF SAME PLACE.

SHOE-SOLE-EDGE SETTER.

SPECIFICATION forming part of Letters Patent No. 375,074, dated December 20, 1887.

Application filed September 29, 1887. Serial No. 251,001. (No model.)

To all whom it may concern:

Be it known that I, LEVI C. KENTON, a citizen of the United States, residing at Baltimore, in the State of Maryland, have invented certain new and useful Improvements in Shoe-Sole-Edge Setters, of which the following is a specification.

My invention relates to a machine for setting the edges of shoe-soles and burnishing the same.

The invention is illustrated in the accompanying drawings, in which—

Figure 1 is a side elevation of the machine. Fig. 2 is a top plan of same. Fig. 3 is a vertical cross-section on the line 3 3. Fig. 4 is a cross-section on line 4. Fig. 5 is a cross-section on line 5. Fig. 6 is a side view of the lower crank-shaft. Fig. 7 is a front view of the adjustable crank-head. Fig. 8 is a view 2c of the crank-collar. Fig. 9 is a sectional view of the tool-holder. Fig. 10 is a front view of the tool-holder.

The letter A designates the stand, supported on legs a. A driven shaft, b, is below the stand, and is supported by bearings b'. A drive-pulley, c, and a loose pulley, c', are on this shaft, and at each end is a crank-head, d, to which is attached an upward-projecting rod, e.

Above the stand are two oscillating shafts, 30 F, each independent of the other, and both supported in bearings g g', and having position end to end and in line with each other. The object of having two separate shafts F is to enable two operators to work at the machine and not interfere with each other. The ends of both shafts F occupy the same central bearing, g', and there is space sufficient in said bearing between the ends for a separating-block, h.

Each shaft F has a collar, C, which is connected by a groove, i, and feather i', (see Figs. 2 and 4,) so as to permit the collar to move lengthwise, but not to turn on the shaft. A spiral spring, j, surrounds each shaft between the said collar and the central bearing, g', and serves to keep the collars pressed in one direction. The collar C has near one end an annular or circumferential groove, k, and a lever, L, has one end pivoted at l to the stand-top, and has an upward-projecting lug, k',

which takes into the said groove k. The free end of the lever has a knob, l', to be grasped by the hand. By moving this free end of the lever toward the central bearing, g', the spiral spring j will be compressed and the one collar 55 C moved lengthwise on the shaft toward the central bearing, g'. The collar C has at one end two lugs, m, which project in line with the shaft. A crank-collar, N, is loose on the shaft F, and may be oscillated thereon freely. 60 It has a crank-arm, n, which is longer than the throw of the wrist d' on the crank-head d, and the rod leading from the said crank-head on the lower shaft connects with the arm n on the crank-collar N.

The crank-collar is provided on its end with two notches, m', to receive the lugs m on the sliding collar. When the spiral spring j presses the collar C endwise, the lugs m will enter the notches m', thereby connecting the loose crank-collar N rigidly with the oscillating shaft F, and thereupon the revolving motion of the drive-shaft b will impart an oscillating motion to the shaft F.

From this description it will be seen that two 75 independent oscillating shafts, F, are connected with one drive-shaft, b. While the machine is thus constructed double, it may be made and used single—that is, with only one shaft F. At the end of each oscillating shaft F is a 80 head or tool-holder, I, which is reversible on the said shaft. This holder carries two burnishing-tools, o and p, one of which is set diametrically opposite the other. The tool (either o or p,) which may be sitting lowermost 85 or pointing downward is the one in position for use. This lowermost tool is in position to receive the jet-flame q from a gas-pipe, q', and the tool is thereby heated. A suitable hand-support, r, is fixed to the stand. The one to 90 the right of Fig. 1 consists of a disk, r, having a central pivot, r'. The back of the operator's hand, which may be grasping the shoe, is placed against this pivoted disk. The one to the left of Fig. 1 consists of a hook, r'.

The tool-holder I is centrally pivoted at the end of the oscillating shaft F, and secured by a bolt, s, and the shaft has a spring-bolt, t, which is moved back by a thumb-piece, t'. One end of the spring-bolt t enters one of the 95 100

two holes *u* in the holder *I* and retains the latter at either position to which it may be set. The object of having two tools, *o p*, on the one holder and making the said holder reversible is to use two tools, each having a burnishing-face of different design—one tool suited for setting the edge of the sole around the broad part of the tread and toe, and the other tool for setting the edge of the sole at the shank or bottom hollow of the sole.

Both tools *o* and *p* are detachable from the holder by loosening the set-screw *v*. The burnishing-tools *o p* have a vibrating motion in a vertical plane, produced by the oscillation of the shaft *b*. This vibration may be regulated so as be longer or shorter.

The crank-head *d* is provided with an adjustable wrist, *d'*, to which the rod *e* is attached. This wrist *d'* is attached to a plate, *w*, which has slots *x*, and occupies a diametrical groove, *w'*, on the crank-head. Each slot in the wrist-plate *w* is occupied by a set-screw, *y*, on the crank-head, and thereby the wrist-plate may be adjusted so as to locate the wrist *d'* at any desired distance from the center of the crank-head, and thus shorten or lengthen the vibration of the burnishing-tool.

The lever *L* carries a hook, *z*, provided with a downward prong, *z'*, which engages with a hole, *z''*, in the stand-top. When the lever *L* is moved to withdraw the collar *C* from engagement with the crank-collar *N*, this hook *z* will retain the lever to the moved position and prevent the spring *j* from forcing it back.

The operation will be readily understood from the foregoing description. The lower tool, which does the work on the edge of a shoe-sole, has a rapid vibrating motion, which is peculiarly well suited to produce good results on the leather.

Having described my invention, I claim and desire to secure by Letters Patent of the United States—

1. A shoe - burnishing machine having, in combination, a driven shaft, *b*, provided with two crank-heads, *d*, two oscillating shafts, *F*, both provided with a crank-arm, *n*, and a burnishing - tool, each independent of the other, and a rod, *e*, connecting each of the said crank-heads with one of the crank-arms. 45

2. A shoe - burnishing machine having, in combination, a driven shaft, *b*, provided with a crank-head having an adjustable wrist, *d'*, an oscillating shaft, *F*, having a crank-arm, *n*, and provided with a tool-holder and tool, and a rod, *e*, connecting the adjustable wrist and crank-arm. 50 55

3. A shoe - burnishing machine having, in combination, a driven shaft, *b*, provided with a crank - head, an oscillating shaft provided with a collar, *C*, having lugs *m*, and so connected with the shaft as to move lengthwise, but not turn, a spring, *j*, pressing against said collar, a crank-collar, *N*, having an arm, *n*, and notches *m'*, and mounted loose on the oscillating shaft, and a rod, *e*, connecting the said crank - head with the arm of the crank-collar. 60 65

4. A shoe - burnishing machine having, in combination, a driven shaft, *b*, provided at each end with a crank-head, *d*, two oscillating shafts, *F*, both provided with burnishing-tools, and each having position end to end and in line with each other, two crank - collars, *N*, each having an arm, *n*, and each mounted on a different one of the oscillating shafts, a clutch-collar, *C*, on each shaft, and rods *e*, connecting the crank-heads with the arms of the crank-collars. 70 75

In testimony whereof I affix my signature in the presence of two witnesses.

LEVI C. KENTON.
